Fig. 1

Technical cross-sectional diagram of a mechanical assembly, labeled Fig. 1. The diagram shows a complex assembly of various components including a main housing, a central cylinder, and various mechanical parts labeled with numbers 1 through 46 and 28a. A large cylindrical component labeled 29 is shown at the bottom left, and a circular component labeled 33 is at the top right. The diagram is highly detailed, showing internal structures like springs and pins.

MACHINE FOR GRINDING AND MAKING
READY PRINTING PLATES

Karl Krüger and Lambert Koop, Bielefeld, Germany, assignors to Fischer & Krecke G. m. b. H., Bielefeld, Germany, a limited stock-company of Germany.

Application November 26, 1938, Serial No. 242,500
In Germany November 14, 1936

11 Claims. (Cl. 51—125)

The object of the invention is to provide a machine for grinding and making ready rubber printing plates in the operation of which the front side of the plate can be observed during the 5 grinding of the back side, so that a satisfactory treatment of the plate is assured.

In grinding machines previously known the printing plate lies with the picture or type downward and the rear side of the printing plate is 10 operated upon by a grinding wheel from above, so that observation of the front side during the grinding process is not possible.

There is a grinding device for printing plates in which the tool holder is mounted so as to be 15 movable in vertical direction with reference to the printing plate and the grinding tool is driven through a flexible shaft. This machine is the grinding device which serves for removing material from individual places on metal printing 20 plates. Accordingly the grinding device works upon the upper side of the printing plate from above. According to the invention a grinding wheel is mounted in a supporting table so that it works upon the back side of the printing plate 25 resting upon the table, while those parts of the back side of the printing plate which require grinding are pressed down from above against the grinding wheel by means of a stamp.

In accordance with a further development 30 of the invention a rotary stamp head is provided with a plurality of pressing faces of different size and shape, which can be selectively brought into operative position, and which are moved against the printing plate by suitable means, 35 such as a hand or foot lever. In accordance with the invention the minimum distance from the grinding wheel to the stamp face can be adjusted to fractions of a millimeter by means of a fine thread, according to the desired thickness 40 of the rubber printing plate.

The supporting table preferably has openings through which the rubber dust formed in the grinding process can be sucked away downward.

The invention is illustrated by one embodiment 45 shown in the accompanying drawings, wherein—

Fig. 1 is a side view, partly in section, of a grinding machine in accordance with the invention;

Fig. 2 is a front elevation showing the mechanism for operating the stamp;

Fig. 3 is a vertical section through a part of the supporting table, taken axially of the grinding wheel;

Fig. 4 is a plan view of the supporting table;

Fig. 5 is a front view of the stamp head showing

an auxiliary device for grinding the lines of the printing plate, a portion of the table appearing in vertical section; and

Fig. 6 is a similar view showing another form of grinding device for type.

To a supporting table 1 is rigidly connected an arm 2, in the forward part 3 of which is a vertical bore holding a shaft 4 in a manner permitting longitudinal movement. The lower part of the shaft is formed as a head 5 containing a horizontal bore lined with a bushing 6. Rotatably mounted in the latter is a shaft 7 of a stamp holder 8, bearing stamps 17, 18, 20 which can be selectively brought into the operative downwardly directed position by rotating the 10 stamp head and which have pressing faces of different size and contour. The stamp holder 8 is drawn against the shaft head 5 by a spring 9 and the shaft head and stamp are provided with interengaging tongue and groove devices 11 to 20 hold the stamp head in any selected position.

The end 3 of the arm 2 has an upwardly facing internally threaded cup surrounding the shaft 4 and into this cup is screwed an externally threaded bushing 12, which is to serve as a stop 25 to limit the downward stroke of the stamp head and to provide an adjustment for compensating for the wear of the grinding wheel. The shaft 4 is provided with a fine thread upon which is screwed a round nut 14, which coacts with the 30 upper face of the bushing 12. The nut 14 bears a cap 15 on which is marked a scale, which cooperates with a pointer 16 (Figs. 1 and 2) mounted on the arm head 3, thus providing for adjustment of the nut by fractions of a millimeter. Fig. 1 shows the lowest position of the stamp holder 8, in which the nut 14 rests upon the upper face of bushing 12. Between the stamp 35 17 on holder 8 and the table 1 is a space which corresponds to the thickness to which the rubber 40 printing plate is to be ground.

The table 1 has on its under side a thickened flange 19 to which is screwed a ring-shaped bearing member 21. In the bearing member 21 (Figs. 1 and 3) the shaft 22 of a fan wheel 23 is rotatably mounted in vertical position. The fan serves to draw through the openings 24 in table 1 the rubber dust arising from the grinding of the rubber printing plates, which is then conveyed off through a conduit connected to the nipple 25. 50 The fan wheel shaft 22 is hollow and internally threaded at its lower end. The lower end of shaft 26 of the grinding disk 27 is externally threaded and is screwed into the threads of the shaft 22. A nut 28 serves to lock the shaft 26 55

to the shaft 22, so that the grinding wheel 27 and fan wheel 23 form a rigid unit. A second nut 28a is fixed by a pin to the lower end of the shaft 26 and acts both as a handle for adjusting the shaft 26 in axial direction and as a stop for limiting the axial adjustment when the grinding wheel has been worn away to a large degree.

Upon the lower end of the fan wheel shaft 22 is fastened a belt pulley 30, which is turned by a belt 31 driven by an electric motor 29; thereby the fan wheel 23 and grinding wheel 27 are rotated.

The following means are provided for moving the stamp holder 8 toward the grinding wheel 27 and against the rubber printing plate lying between the grinding wheel and the pressing stamp 17, 18, or 20:

In the table 1 is rockably mounted a shaft 32, the outer end of which bears a head or a plate 33, which can be operated by the knee of the worker. By the pressure of the knee the shaft 32 is rocked, whereby a thrust rod 41 is raised, through the intermediary of a lever 34, a pin and slot connection 35, 36 (Fig. 2), a lever 37, a shaft 38, and a lever 39. The thrust rod 41 acts upon a lever arm 42 fastened to a shaft 44, to which is also secured a lever arm 43. The shaft 44 is rockably mounted in the machine arm 2. The lever arm 43 has a slot 45 embracing a pin 46 which projects from the shaft 4 through a slot 46a in the arm head 3.

The described machine can also be made so as to be converted at will from a machine for grinding and making ready into a type and line grinding machine. For the latter purpose the following additional devices are provided:

At a suitable place, for example, on the side of the machine, a special electric motor 59 (Figs. 5 and 6) is mounted, which transmits a driving motion through a flexible transmission shaft 51 to a holder 52. The holder 52 can either be mounted in place of the stamp holder 8 upon the shaft 7, or, as the example in the drawings shows, can be screwed upon one of the pressing stamps of the stamp holder 8, for instance, the stamp 17. In Fig. 5 the holder 52 is so positioned that the drive shaft lies horizontally and a conical grinding disk for working upon or producing lines can be used. In Fig. 6 the drive shaft in the holder 52 is vertical, so that a grinding rod for working or grinding individual type can be used.

When the device is used for grinding type or lines, the drive of the grinding wheel 27 is stopped.

The manner of operation of the described machine, in brief recapitulation, is as follows:

By means of the bushing 12 an adjustment can be made to compensate for wear of the grinding wheel 27, so that the indication of the pointer 16 upon the scale on cap 15 will be accurate.

By means of the cap 15 fastened to the nut 14 that one of the three pressing stamps 17, 18, 20 which is in operative position can be finely adjusted according to the desired thickness of the printing plate being worked upon. The latter is laid upon the table 1 with its back side down over the grinding wheel 27, so that the portion to be ground lies under the stamp 17, 18, or 20 which is in operative position.

When the adjustment has been completed, the operative stamp is pressed toward the grinding wheel 27 by the lever 33, so that the back side of the printing plate is ground off. The switching on of the electric motor 29 for driving the grinding wheel 27 and the fan wheel 23 can be made

to take place simultaneously with the movement of lever 33, or by a special switch device. During the work the rubber printing plate can easily be observed from above.

If individual lines or type of the printing plate are to be worked upon, the holder 52 is screwed on to the stamp holder 8 and, according to the desired method of operation, a grinding disk like Fig. 5, or a grinding rod like Fig. 6 is set on.

We claim:

1. In a grinding machine for rubber printing plates, a table to support the printing plate having a hole therein, a grinding wheel mounted in said hole so that its face is approximately at the level of the surface of the table, a stamp head mounted for up and down movement above the table and having a plurality of faces of different area, said stamp head being also rotatable to bring a selected one of said faces into position to press a portion of the printing plate against the grinding wheel, and means for moving the stamp head up and down.

2. In a grinding machine for rubber printing plates, a table to support the printing plate having a hole therein, a grinding wheel mounted in said hole so that its face is approximately at the level of the surface of the table, a stamp head mounted for up and down movement above the table and having a face adapted to press a portion of the printing plate against the grinding wheel, manipulative means for moving the stamp head up and down, means for limiting the movement of the stamp head toward the grinding wheel, and means for finely adjusting said limiting means.

3. In a grinding machine for rubber printing plates, a table to support the printing plate having a hole therein, a grinding wheel mounted in said hole so that its face is approximately at the level of the surface of the table, an arm overhanging the table, a stamp head mounted for up and down movement on said arm and having a face adapted to press a portion of the printing plate against the grinding wheel, a second grinding means, and means whereby the latter can be supported from said arm so as to be movable into and out of contact with the upper surface of the printing plate.

4. In a grinding machine for rubber printing plates, a table to support the printing plate having a hole therein, a grinding wheel mounted in said hole so that its face is approximately at the level of the surface of the table, means movably supported above the table for pressing the printing plate to the grinding wheel, said table having openings therethrough adjacent said grinding wheel hole, and means for drawing air downward through said openings.

5. In a grinding machine for rubber printing plates, a table to support the printing plate having a hole therein, a grinding wheel mounted in said hole so that its face is approximately at the level of the surface of the table, an arm rigidly overhanging said table having a vertical bore in its forward part, a vertical shaft movable longitudinally in said bore, and a stamp head comprising a supporting shaft, said vertical shaft having a horizontal bore at its lower end to receive said stamp head shaft, said stamp head having a pressing face adapted to push a portion of the printing plate against said grinding wheel.

6. In a grinding machine for rubber printing plates, a table to support the printing plate having a hole therein, a grinding wheel mounted in said hole so that its face is approximately at the level of the surface of the table, an arm rigidly

- overhanging said table having a vertical bore in its forward part, a vertical shaft movable longitudinally in said bore, a stamp head comprising a supporting shaft, said vertical shaft having a horizontal bore at its lower end to receive said stamp head shaft, said stamp head having a plurality of pressing faces of different area adapted to be brought selectively into operative position by rotating said stamp head on its shaft in said horizontal bore, the operative pressing face being adapted to push a portion of the printing plate against said grinding wheel.
7. A grinding machine as described in claim 6, wherein said stamp head and said vertical shaft are provided with interengaging tongue and groove devices to hold said stamp head in a selected position, and a spring is provided to hold said stamp head against said vertical shaft.
8. In a grinding machine for rubber printing plates, a table to support the printing plate having a hole therein, a grinding wheel mounted in said hole so that its face is approximately at the level of the surface of the table, an arm rigidly overhanging said table having a vertical bore in its forward part, a vertical shaft movable longitudinally in said bore, a stamp head comprising a supporting shaft, said vertical shaft having a horizontal bore at its lower end to receive said stamp head shaft, said stamp head having a pressing face adapted to push a portion of the printing plate against said grinding wheel, said vertical shaft being threaded with fine threads at its upper end, a nut screwed onto said threads, said arm having an upwardly opening internally threaded cup surrounding said vertical shaft below said nut, and an externally threaded bushing screwed into the threads of said cup and serving as a stop limiting the downward movement of said vertical shaft.
- 40 9. A grinding machine as described in claim 8, wherein said nut is provided with a cap marked with a scale, and said arm is provided with a pointer coacting with said scale.
10. In a grinding machine for rubber printing plates, a table to support the printing plate having a hole therein, a grinding wheel mounted in said hole so that its face is approximately at the level of the surface of the table, means movably supported above the table for pressing the printing plate to the grinding wheel, said table having openings therethrough adjacent said grinding wheel hole and a thick flange on its lower side surrounding said openings, a bearing member having a flange fixed to said thickened flange, a suction fan rotatably mounted in said bearing member below said openings, and means for rotating said fan.
11. In a grinding machine for rubber printing plates, a table to support the printing plate having a hole therein, a grinding wheel mounted in said hole so that its face is approximately at the level of the surface of the table, means movably supported above the table for pressing the printing plate to the grinding wheel, said table having openings therethrough adjacent said grinding wheel hole and a thick flange on its lower side surrounding said openings, a bearing member having a flange fixed to said thickened flange, a suction fan below said openings having an internally threaded hollow shaft rotatably mounted in said bearing member, said grinding wheel having an externally threaded shaft screwed into said hollow shaft, means for locking said grinding wheel shaft in a set position in said hollow shaft, and means for rotating the unit comprising said fan and said grinding wheel.
